Des. 204,784
Patented May 17, 1966

204,784

TRAY FOR TOILET ARTICLES OR THE LIKE

Robert A. O'Neil, Pittsburgh, Pa., assignor to Fesco, Inc.,
New York, N.Y., a corporation of Delaware

Filed July 8, 1965, Ser. No. 86,087

Term of patent 14 years

(Cl. D44—10)

FIGURE 1 is a top plan view of a tray for toilet articles or the like showing my new design;

I claim:

The ornamental design for a tray for toilet articles or the like, as shown.
